UNITED STATES PATENT OFFICE

146,884

DESIGN FOR AN AUTOMOTIVE VEHICLE

Russell P. Sweger, Rockford, Ill.

Application February 8, 1946, Serial No. 126,376

Term of patent 7 years

(Cl. D14—3)

To all whom it may concern:

Be it known that I, Russell P. Sweger, a citizen of the United States, residing at Rockford, in the county of Winnebago and State of Illinois, have invented a new, original, and ornamental Design for an Automotive Vehicle, of which the following is a specification, reference being had to the accompanying drawings, forming a part thereof.

In the drawings:

Fig. 2 is a side elevational view.

Fig. 3 is a top plan view.

I claim:

The ornamental design for an automotive vehicle, substantially as shown.

RUSSELL P. SWEGER.
